Rudolph Koch, Inventor

Rudolph Koch, By *Rudolph Koch,*

Attorney

UNITED STATES PATENT OFFICE.

RUDOLPH KOCH, OF MILWAUKEE, WISCONSIN.

STORAGE-BATTERY TERMINAL.

Application filed December 14, 1925. Serial No. 75,370.

This invention relates to a storage battery terminal.

One object is to provide a two section battery terminal combined with a locking device to provide for an easy installation and removal of the terminal from the battery post and to permit of easy cleaning of the terminal parts in the event of corrosion.

Another object resides in the provision of a battery terminal constituted to provide for a tight, non-slip connection with the battery post such as will prevent a loose connection and consequent battery trouble.

A still further object is to provide a simple, inexpensive and effective storage battery terminal, embodying among other characteristics, structural features providing for an adjustable connection with the battery post so as to eliminate the use of lead strips, etc., and yet permit use of the terminal on various sized posts.

It is still further designed to provide a battery terminal embodying separable parts which may be easily and readily assembled and as easily and readily disassembled to provide for cleaning and replacement of parts, if necessary, and wherein with little or no difficulty the terminal may be applied to or removed from the battery post.

With the above and other objects in view, the invention consists in the construction and novel combination and arrangement of parts hereinafter, fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a plan view, parts being broken away;

Fig. 2 is a sectional view on the line 2—2 of Fig. 1;

Fig. 3 is a side elevation.

Referring now more particularly to the accompanying drawings, the reference character 4 indicates a substantial mass of suitable material forming a body provided at one end with a socket 5 adapted to receive and secure the wire 6 designed to connect the battery post 7 electrically with an ignition or lighting system (not shown). The

opposite end of the body 4 is bifurcated, providing spaced ears 8 connected adjacent their outer ends by a hinged pin 9 for a purpose presently explained

The body 4 is adapted to support not only one end of the wire 6 but it also is adapted to support suitable means for connecting the terminal with the battery post 7. To this end, an arm 10 projects laterally from one side of the body 4 intermediate the ends of the latter and adjacent the body 4, the arm is curved to form a clamping surface 11 provided with a rib 12 adapted to press or bite into the lead post on the battery, as will be presently explained.

An arm 13, provided with a curved portion forming a clamping surface 14, is adapted to cooperate with the clamping arm 10—11 to secure the terminal to the battery post. This second arm is of somewhat peculiar shape in that it has its inner end reduced in width as at 15, to form curved shoulders 16, one on each side of the reduced portion adjacent the curved clamping surface 14 with the clamping surface 11 of the arm 10 and thereby provide for an effective binding action of the terminal on the battery post. The outer end of the reduced portion is bifurcated to form a hook 17 adapted to pass between the ears 8 of the body 4 and swingingly hook over the aforesaid hinge-pin 9 whereby to provide for a swinging movement of the clamping arm 13—14 into and out of cooperative relation with the clamping arm 10—11 to effect a connection or disconnection of the terminal with the battery post 7.

By virtue of the hook connection of the clamping arm 13—14 with the body 4 and the latter carrying the clamping arm 10—11, the two pieces or sections of the terminal may be easily and readily assembled and as easily and readily separated or taken apart for cleaning or replacement purposes. If the terminal should corrode, it is possible with the present terminal to take it apart easily, clean and use it again.

The terminal is fastened or locked onto the battery post 7 by means of a bolt 18 and nut 19, the bolt passing through the oblong apertures 20 in the outer ends of the clamping arms. By tightening the nut the rib 12 of the clamping surface 11 is caused to press or bite into the lead battery post, providing for a tight, non-slip grip on the post not likely to be jarred loose incident to vibration

or jars due to rough roadways. Moreover, the form of clamping means employed is such as to be readily adjustable to coact with various sized battery posts, eliminating the use of lead strips, etc. to take up slack, and by virtue of the form and ready removal of the terminal from the post the latter is readily accessible for cleaning purposes, if corroded, without danger of breakage of 10 either the post or the terminal, no twisting of the post engaging parts being necessary to effect the disconnection between terminal and post.

It will be understood that the terminal 15 may be composed of brass, lead coated or composed of non-corrosive metal or of any metal deemed suitable for the purpose and that the rib 8 may be formed in either of the clamping surfaces of the arms or both, 20 as may be desired.

What is claimed is:—

A battery terminal, comprising a body

provided at one end with a wire receiving socket and at its other end with spaced ears, an arcuate clamping arm extending laterally 25 from said body intermediate its ends and terminating in an ear having an opening therein, a hinge pin between the ears on the body, a second arcuate clamping arm having a reduced end provided with a hook adapted to 30 pass between the ears and detachably engage the hinge pin and terminating in an ear on its other end having an elongated opening 35 therein, a bolt passing through the openings in the ears on the clamping arms to accommodate the terminal to battery posts of different sizes and clamp the same thereto, and a horizontal rib on one of the clamping arms adapted to bite into the battery post when the arms are forced together. 40

In testimony whereof I have hereunto set my hand.

RUDOLPH KOCH.
